UNITED STATES PATENT OFFICE.

FRITZ FISCHLI, OF NAFELS, SWITZERLAND.

HAND EMBROIDERING MACHINE.

Application filed March 31, 1921. Serial No. 457,470.

(GRANTED UNDER THE PROVISIONS OF THE ACT OF MARCH 3, 1921, 41 STAT. L., 1313.)

To all whom it may concern:

Be it known that I, FRITZ FISCHLI, a citizen of the Republic of Switzerland, residing at Nafels, Switzerland, have invented certain new and useful Improvements in Hand Embroidering Machines (for which I have filed applications in the following countries: In Switzerland, April 3, 1915, Patent No. 70128; in Germany, March 2, 1918, Patent No. 308,930; in France, March 11, 1918, Patent No. 489,257; in Switzerland, November 23, 1918, Patent No. 81716; in Italy, July 8, 1919, Application No. 281/1770; in England, January 10, 1921, Patent No. 157410; in England, January 10, 1921; Patent No. 157411); and I do hereby declare the following to be a clear, full, and exact description of the invention, such as will enable others skilled in the art to which it appertains to make and use the same, reference being had to the accompanying drawing, and to letters or figures of reference marked thereon, which form a part of this specification.

25 In order to increase the output of hand embroidering machines it is necessary to shorten the stroke for a certain draw of the thread.

The object of the present invention is to provide a device of simple construction, which in connection with hand embroidering machines shortens the stroke of the carriage and considerably increases the output.

For this purpose, the device according to the present invention comprises arms rigidly connected to the shafts carrying the thread-drawers or take ups, which are mounted in the usual manner in the carriage of the hand embroidering machine, said arms being flexibly connected to bars, pivoted at one end and causing a toggle like motion to take place between them and the said arms during the outward stroke of the carriage, so that the thread drawers are impelled downwards in such a manner as to cause the threads to fold into a loop.

Weights may preferably be attached to the shafts carrying the thread drawers, causing a toggle like motion between the bars and the arms, upon the return of the carriage, so that the thread-drawers receive an upwardly directed impulsion, causing the thread to be released.

It is further possible, in case the device

according to the present invention is intended to be used in connection with embroidering machines the carriages of which comprise thread drawers supported by two superposed shafts, to dispose the arms on the upper, and the weights on the lower shaft, the two shafts being desirably connected by gearing.

In order to make clear the above invention it will now be more particularly described with reference to the accompanying drawing which illustrates two constructional examples of the same.

In this drawing

Fig. 1 is a side view of a hand embroidering machine fitted with the device according to the present invention, only the parts of the machine necessary for the comprehension of the invention being shown.

Fig. 2 is a part plan view of Fig. 1.

Fig. 3 is a detail of the new device.

Fig. 4 is a side view of a similar hand embroidering machine fitted with a device according to the present invention, wherein the bars, pivoted at one end, may be disconnected from the arms.

Fig. 5 is a front view of the machine according to Fig. 4. The hand embroidering machine partly shown in Figs. 1 and 2 is an embroidering machine of the double rowed type, with carriages 1, movable to and fro along the rails 2. The two ends of each carriage 1 are connected together by a shaft 3 extending over the whole length of the machine and carrying the needle holders 4 in the well known manner, on upper and lower slides held by supports 3^a. At each end of the machine, a bar 5, rotatable around point 21 is fixed to the frame 6 and cooperates by means of one of its notches 7, with a protruding pin 9 of an arm 8, which latter is adjustable lengthwise in a carrier socket 10. A thread drawer 11 extends over the whole length of the machine, and is bent over at its ends which are adjustably fixed in the sockets 10. The two sockets 10 are rigidly mounted on the ends of a shaft 13 mounted in supports 3^a of the carriage.

The sockets 10 of the lower row hold only the ends of the lower thread drawer 11, and no arm 8. Screws 12 and 14 serve respectively to fix the arms 8 and the thread drawer 11 in the sockets 10, which latter are in turn held in place on shafts 13 by means

of screws 15. On each shaft 13 of this double-rowed embroidering machine is mounted a toothed wheel 16. A perforated steel band 17 cooperates with each of the wheels 16 and is stretched by means of a roller 18. A balance weight 19 is fitted to the lower shaft 13 of each carriage 1. Supports 20 (Fig. 3), mounted on shafts 13, serve to prevent a deformation of the thread drawers 11 due to the tension of the thread.

As far as described the machine works as follows: Let it be supposed that the carriage 1, shown in Fig. 1 in its inner position, is to be moved outwardly. The bars 5 on each side of the machine are swung outwardly by means of the arms 8, which latter, together with the bars 5 execute a toggle like motion. All movements of the upper shaft 13 are transmitted to the lower shaft 13 of the lower row by means of the toothed wheels 16 and band 17, causing thereby the thread drawers 11 to be impelled downwards, and the folding into a loop of the thread drawn out of the fabric 24 by means of the needle holders 4.

After the carriage has attained its outer position and the threads have been completely drawn out downwardly by means of the thread drawers 11 (right side of Fig. 1), it returns to its inner position. The balance weight 19 tends to maintain the arms 8 in their operative position with regard to bars 5 so that said parts execute an inwardly directed toggle like motion, whereby the thread drawers 11 are impelled upwards, releasing the threads in the necessary manner. When the carriage 1 has reached the end of its return stroke, the parts once more assume the position shown on the left half of Fig. 1, whereupon, after the needles have pierced the fabric 24, the threads are withdrawn through the corresponding parts of the right hand carriage which are opposite to those of the left hand carriage. The stroke of the carriage can be adjusted by placing the pins 9 in one or the other of the notches 7 of bars 5.

It will be appreciated that the stroke of the carriage is considerably shorter than usual because of the pulling down of the threads by means of the thread drawers.

In Fig. 3 the arms 8 and the thread drawers 11 are shown connected at each end to separate sockets 22, 23.

The hand embroidering machine shown in Figs. 4 and 5 is a double rowed machine with carriages 1, movable to and fro along rails 2, the ends of each carriage being connected together by means of shafts 3 extending over the whole length of the machine. Shafts 3 carry needle-holders 4 on slides held by supports 3^a. Bars 5 are linked at one end 21 to frame 6 of the embroidering machine, they presenting notches 7, of which one cooperates with a pin 9 of an arm 8 so

as to form an articulated connection between the bar and the arm. Each arm 8 is adjustably fixed in a socket of a member 10 in which is also movably fitted the bent over end of thread drawer 11 extending over the whole length of the machine, the other end of said thread drawer being also bent over and fitted in a member similar to member 10 at the other end of the machine, in which is fixed another arm 8 cooperating with a bar 5. Both members are rigidly connected to the ends of a shaft 13 mounted in the above mentioned supports 3^a.

The swinging motion required to draw out the thread is imparted to the thread drawers 11 by means of bars 5 and arms 8 from the reciprocating motion of the carriage 1. It may be desirable that the bars 5 and arms 8 be capable of being disconnected or that it become necessary, in order to modify the stroke of the thread drawer 11, to engage the pins 9 of arms 8 with other notches 7 of the bars 5. In order to render such a movement of bars 5 possible, there are provided two shafts 25 extending over the whole of the upper part of the machine, rotatably mounted and longitudinally displaceable. A lever 26 with a bent over end 27 is fixed near each end of the shafts 25. Levers 26 of each shaft 25 ensure of a movement of bars 5 respectively at either side of the frame 6. Each shaft 25 is fitted with a handle 28 and has attached thereto a balance weight 29, tending to move levers 26 in the direction of the arrow A, the handles 28 serving to adjust shafts 25 in order that levers 26 should occupy the positions indicated by full lines in Fig. 5 and on the left side of Fig. 4, that is to say completely out of range of bars 5.

Is it desired to disconnect bars 5 from arms 8, shafts 25 are turned by means of handles 28 so that levers 26 pass from position indicated by dotted lines on the right side of Fig. 4 into that shown in full lines, whereupon shaft 25 is longitudinally displaced in such a manner that the bent over ends 27 of levers 26 are brought into the position indicated by dotted lines in Fig. 5, so that they lie against arms 5 from the underneath side.

Upon releasing handle 28 of a shaft 25 when the levers 26 are in this position, the balance weight 29 produces a turning movement of said shaft 25 in such a manner that the two levers 26 fixed thereto be moved in the direction of arrow A, whereupon the bars 5 swing around their pivoted ends 21, till they come to occupy the position indicated by dotted lines on the right side of Fig. 4, quite out of range of arms 8. Is the shaft 25 now turned by means of the handle in such a manner that levers 26 move in the direction of arrow B against the action of weight 29, the bars

5 may again be connected to arms 8 by means of a pin 9 when carriage 1 is in a suitable position. By suitably adjusting carriages 1 and lowering of levers 26 it is possible to 5 determine the cooperation of one certain notch 7 of bars 5 with one certain pin 9 of arms 8.

In case a bar 5 pivoted to frame 6 be also provided in connection with each arm 10 8 of the lower row, it will be possible to connect those bars 5 of different rows which are situated one above the other, by means of a chain or band, so that each movement imparted to bars 5 of the upper row by 15 means of levers 26 be transmitted to bars 5 of the lower row.

It is to be understood that the invention is by no means limited to the embodiments here illustrated and described by way of example.

I claim:

1. In a hand embroidering machine, a device for shortening the stroke of the carriage when drawing out the thread comprising in combination a frame, a carriage thereon, shafts mounted in the carriage, thread drawers carried by the shafts, bars having their inner ends pivotally connected to the frame, arms rigidly connected to the shafts and flexibly connected to the outer ends of the bars whereby a toggle like motion is produced between the bars and arms during the outward stroke of the carriage so that the thread drawers are impelled downwardly to cause the threads to fold into a loop.

2. In a hand embroidering machine, a device for shortening the stroke of the carriage when drawing out the thread comprising, in combination a frame, a carriage thereon, shafts mounted in the carriage, thread drawers carried by said shafts, balance weight fixed to said shafts, bars pivotally connected to the frame, arms rigidly connected to the shafts and flexibly connected to the bars whereby a toggle like motion occurs between the bars and arms during the outward stroke of the carriage so that the thread drawers are impelled downwardly to cause the threads to fold into a

loop, said weight effecting an inwardly directed toggle like motion between the bars and the arms during the inward stroke of the carriage whereby the thread drawers are impelled upwardly to release the threads. 55

3. In a hand embroidering machine, a device for shortening the stroke of the carriage when drawing out the thread comprising in combination, a frame, a carriage operable on the frame, shafts journalled in the carriage, thread drawers carried by the shafts, bars pivotally connected to the frame, arms connected to the shafts and flexibly connected to the bars for producing a toggle like motion between the bars and arms during the outward stroke of the carriage, to impel the thread drawers downwardly so as to fold the threads into a loop, members pivotally mounted on the frame for disconnecting the bars from the arms on which they cooperate and balance weight for automatically moving said bars out of range of the arms when the shafts are released after said members have been brought into the range of the bars. 75

4. In a hand embroidering machine, a device for shortening the stroke of the carriage when drawing out the thread, comprising in combination a frame, a carriage 80 slideable thereon, shafts journalled in the carriage, thread drawers carried by the shafts, arms connected to the shafts, bars operably connected to the frame and to the arms for producing a toggle like motion between the bars and arms during the outward stroke of the carriage so that the thread drawers are impelled downwardly to cause the threads to fold into a loop, members in the form of levers bent over at their 85 free ends swingably mounted on the frame for disconnecting the bars from the arms with which they cooperate, and balance weight automatically moving said bars out of range of the arms when the shafts are released and after said members have 90 been brought into the range of the bars. 95

In testimony that I claim the foregoing as my invention, I have signed my name.

FRITZ FISCHLI.
